UNITED STATES PATENT OFFICE.

SERGE DANILOFF, OF LOWELL, MASSACHUSETTS, ASSIGNOR TO SACO-LOWELL SHOPS,
A CORPORATION OF MASSACHUSETTS.GUIDE FOR CONTINUOUS BOBBIN FEED FOR USE IN SPOOLING MACHINES AND THE
LIKE.

Application filed July 28, 1922. Serial No. 578,257.

To all whom it may concern:

Be it known that I, SERGE DANILOFF, a citizen of Russia, residing at Lowell, Massachusetts, have invented certain new and useful Improvements in Guides for Continuous Bobbin Feed for Use in Spooling Machines and the like, of which the following is a specification.

My invention is designed for use in spooling machines or other machines in which yarn or twine is drawn off from containers, such as bobbins; and its purpose is to provide means whereby the yarn may be drawn off from a series of bobbins, the yarn at the lower end of the first of which is tied to the yarn at the top end of the second, so that the feed will not be interrupted by the exhaustion of the yarn on the first bobbin. It is obvious that the use of the herein by which such continuous bobbin feed can be accomplished successfully will materially increase the number of bobbins that can be taken care of by an operator on such a machine, and will decrease the loss of production due to interruption of feed, as compared with the usual system in which the work is interrupted each time that a single bobbin becomes exhausted.

A particular object of my invention is to provide means whereby this continuous bobbin feed may be accomplished without breakage of the yarn during the transition of the winding operation from the first bobbin to the second bobbin. It is a further object of my invention to avoid complexity and a difficult arrangement of parts in such mechanism, as compared, for instance, with previous attempts to accomplish the desired continuous bobbin feed, in which special forms of bobbin clusters with rotating bases have been required and to provide mechanism to this end which shall be readily attachable to forms of spooling machines now in common use, so as to require no material change in the construction thereof.

My invention has the further advantage that it allows the bobbins to be mounted in parallel positions, thereby making for compactness and saving space, as compared with certain arrangements which have heretofore been suggested for the accomplishment of continuous bobbin feed, in which a plurality of bobbins have been mounted in positions

inclined with reference to each other, their several axes being arranged to intersect at a common point.

In the accompanying drawings, Fig. 1 is a front elevation of my invention as applied to a spooling machine, only so much of the machine being shown as is necessary to illustrate the invention. Fig. 2 is a side elevation of the same device.

Referring to the drawings, 1 represents a spool upon which the yarn contained on bobbins 2 and 3 is to be wound. These bobbins are mounted in the usual manner upon bobbins skewers 4 and 5 which skewers are in turn mounted upon the usual skewer rod 6. At 7 is represented a tension device which may be of any known form, which is clamped upon the ordinary tension rod 8. Likewise mounted upon the tension rod 8 and behind the tension device is a thread guide 9 which may be of any usual form. The thread unwound from the bobbins passes through a guide-way 10 leading to the tension device thence through the tension device 7 and thread guide 9 to the spool 1.

All the foregoing instrumentalities are well known, and it is unnecessary to describe them in detail or to describe the mechanism by which the spool 1 is rotated.

Clamped to the tension rod 8 and preferably in the position indicated in Fig. 1, is a guide member 11. This guide member in the preferred form as illustrated has the form of a Y as viewed from the front, and consists of a V-shaped piece of sheet steel having the two arms 12, 12, and attached to the apex thereof, by welding or otherwise, and extending downwardly therefrom, as in view 13. This guide member is supported in position by the two vertically extending arms 14, 14, which are preferably placed one on each side of the tension device and thread guide, these arms having extensions 15 which are clamped to the tension rod 8 in any suitable manner, as by the clamp 16, Fig. 2.

Each of the two arms 12, 12 of the Y-shaped member has its outer edge, at one point on its length, so placed as to substantially intersect the axis of one of the bobbins, as indicated at 17 and 18 respectively. The guide member extends there-

from outwardly, downwardly and again inwardly, as indicated in Fig. 2, preferably to a point below the base of the bobbins and to the rear of the front portions of their

5 bases.

I preferably bend this guide member so that it assumes roughly the shape of a portion of an ellipse when viewed from the side, as indicated in Fig. 2, since this has been 10 found by experiment to be the shape causing the least strain on the yarn. The edges of the guide member are rounded so as not to wear the yarn unduly.

The operation of the device is as follows:—The lower end of the yarn on bobbin 2 having been first tied by the operator to the upper end of the yarn on bobbin 3, as indicated at X, and the tied portion of the 15 yarn being placed outside the glide wire 13, the upper end *a* of the yarn on bobbin 2 is threaded through the tension device, the thread guide, and engaged with the spool, and the spooler set in motion. While the 20 yarn is being drawn off from bobbin 2, the yarn passes over the guide member substantially as indicated in Fig. 1, the position of the "balloon" which the yarn forms during the process of unwinding being roughly indicated at 19, 19. Upon the exhaustion of 25 the yarn on bobbin 2, the tied ends will be drawn upwardly over the outside of the guide until the slack has been taken up and unwinding from bobbin 3 begins. The 30 yarn from bobbin 3 now passes over the guide member at substantially the point 18, and thence to the tension device, thread guide 35 and spool.

By the use of this guide member the transition of the unwinding operation from the 40 first to the second bobbin is made easily and without a sudden jerk, and breakage of the 45 yarn is thus avoided.

This guide member acts, therefore, as a 50 guide for the yarn during the whole process of unwinding, the yarn being guided into a 55 position substantially in the axis of each bobbin during the period of unwinding from such bobbin, and being guided from one of these positions to the other during the 60 transition of the unwinding operation from the first to the second bobbin.

The only mechanism which need be supplied to a spooling machine as ordinarily in use for the purpose of adapting it to continuous bobbin feed in accordance with my 65 invention, is this guide member, which is simple and easy to construct.

It will be obvious that many changes might be made from the form shown in the 70 drawings, without departing from the spirit of my invention.

What I claim as new and desire to secure by Letters Patent is:—

1. In mechanism of the class described, a 75 pair of parallel skewers for bobbins mounted

on the skewer rod, and an intermediately placed guiding member operative during the transition of the unwinding operation from one bobbin to the other.

2. In mechanism of the class described, a 80 pair of skewers for bobbins and a guiding member having two edges for guiding yarn from each of said bobbins respectively, said edges extending in a substantially continuous curve from points beyond the free ends 85 of said bobbins to a common point substantially at the base of said bobbins.

3. In mechanism of the class described, a 90 pair of skewers for bobbins and a guiding member having two edges extending in continuous curves respectively from points beyond the free ends of said two bobbins to a common point near their base.

4. In mechanism of the class described, a 95 substantially Y-shaped guide member having its stem interposed between two parallel skewers and its arms extending beyond the free ends of the skewers.

5. In mechanism of the class described, a 100 pair of skewers for bobbins, a thread guide, and an intermediate Y-shaped guiding member adapted to guide the yarn from the bobbins to the thread guide both while it is being unwound from each bobbin and during the transition of the unwinding operation 105 from one bobbin to the other.

6. In mechanism of the class described, a 110 pair of skewers for bobbins and a guide member substantially Y-shaped, having its stem in a plane substantially parallel to planes containing the axes of the bobbins, and the outer edges of its arms beyond the 115 free ends of said bobbins and approximately intersecting the axes of the bobbins respectively.

7. In mechanism of the class described, a 120 pair of skewers for bobbins and a guide member substantially Y-shaped, having its stem in a plane substantially perpendicular to the plane containing the axes of said two bobbins and its arms extending to points beyond the free ends of said bobbins.

8. In mechanism of the class described, a 125 pair of skewers for bobbins, a Y-shaped guide member having its stem between the axes of the bobbins and its arms extending beyond the free ends of the bobbins, and a thread guide positioned between the arms of said Y-shaped member.

9. In mechanism of the class described, a 130 pair of parallel skewers for bobbins mounted on a skewer rod, a thread guide, and an intermediate guiding member adapted to guide the yarn from the bobbin to said thread guide, both while it is being unwound from the bobbins and during the transition of the unwinding operation from one bobbin to the other.

10. In mechanism of the class described, two skewers for bobbins, a thread guide 135

mounted on a rod, and an intermediate guiding member supported from said rod and operative during the transition of the unwinding operation from one bobbin to the other.

11. In mechanism of the class described, a pair of skewers for bobbins, a guide member having edges extending beyond the free ends of the bobbins, and continuous therewith a portion extending outwardly from the plane of the axes of the bobbins, then lengthwise of the bobbins, and then inwardly to a point near the base of said bobbins.

12. In mechanism of the class described, a pair of skewers for bobbins, a guide member having edges extending to points beyond the free ends of the bobbins and substantially in line with their axes respectively, and continuous therewith a portion extending outwardly from the plane of the axes of the bobbins, then lengthwise of the bobbins, and then inwardly to a point near the base of said bobbins.

13. In mechanism of the class described, a pair of skewers for bobbins, a guide member having rigid portions for guiding yarn while being unwound from said bobbins, and a resilient extension for guiding the yarn dur-

ing the transition of the unwinding process from one bobbin to the other.

14. In mechanism of the class described, a pair of skewers for bobbins, a guide member having rigid portions placed beyond the free ends of said bobbins for guiding yarn while being unwound from said bobbins, and a resilient extension for guiding the yarn during the transition of the unwinding process from one bobbin to the other, the extremity of said resilient extension being between and substantially in line with the bottoms of the two bobbins.

15. In mechanism of the class described, a pair of skewers for bobbins, a guide member having portions for guiding yarn while being unwound from said bobbins, and a portion for guiding the yarn during the transition of the unwinding process from one bobbin to the other, said guide member having substantially the form of a portion of an ellipse as viewed in side elevation and extending from points beyond the free ends of the bobbins to a point near their bases.

In witness whereof, I have signed my name to this specification.

SERGE DANILOFF.
